UNITED STATES PATENT OFFICE.

LOWELL MASON MAXHAM, OF BOSTON, MASSACHUSETTS.

ELECTRIC-THIRD-RAIL SYSTEM.

SPECIFICATION forming part of Letters Patent No. 623,610, dated April 25, 1899.

Application filed April 6, 1898. Serial No. 676,629. (No model.)

To all whom it may concern:

Be it known that I, LOWELL MASON MAXHAM, a citizen of the United States, residing at Boston, in the county of Suffolk and State 5 of Massachusetts, have invented a new and useful Electric Third Rail, of which the following is a full, clear, and exact description.

My invention relates to means whereby the electric current can be transmitted to a car 10 from an electric conductor which is normally insulated within a third rail; and it comprises, essentially, a hollow third rail having an electric conductor within it and normally out of contact therewith, a movable bar 15 exterior to said third rail, means whereby the movement of said bar shall locally complete the circuit between said electric conductor and third rail, and a device carried by the car and adapted to properly operate said bar. 20 Among the devices which I have invented for enabling the electric conductor to be put into contact with the third rail is a series of rocking arms supported at opposite ends of the electric conductor and movable bar in such 25 a manner that the depression of the bar shall automatically elevate and depress the electric conductor into pressing contact with the ceiling of the third rail, and thereby conduct the current to the shoe sliding on the upper 30 surface of said third rail, which shoe is in electric circuit with the motor propelling the car. Another device comprises a laterally-movable slide carrying the electric conductor into contact with the interior of the third rail 35 and adapted to be reciprocated by means of said movable bar.

Referring to the drawings forming part of this specification, Figure 1 is a cross-section of a third rail, the electric conductor located 40 therein, the depressible bar, and the contact-shoe and bar-depressing wheel. Fig. 2 is a side view of a section of the third rail and depressible bar. Fig. 3 is a plan view of the rocking lever or arm carrying the electric 45 conductor and depressible bar. Fig. 4 is a side elevation of the sliding shoe and the bar-depressing wheel carried therewith. Fig. 5 is a horizontal section of the sliding shoe. Fig. 6 is a cross-section of the third rail, showing 50 the manner in which the depressible bar is enabled to move the electric conductor laterally into contact with said rail. Fig. 7 is

a cross-section of the third rail, showing the electric conductor and depressible bar supported by a rocking arm, but with a spacing-rail introduced between said third rail and movable bar. Fig. 8 is a perspective view of said spacing-rail. Fig. 9 is a perspective view of the pivot-spike designed for supporting said rocking arm. Fig. 10 is a cross-section, 60 upon a much smaller scale, of the third rail and allied parts, with the bar-depressing wheel slightly modified.

In all the forms of my invention illustrated, F indicates the third rail, A the electric conductor, and E the movable bar. M is the sliding shoe, designed to transmit the current from the third rail through the shoe-carrier N and the spring-supports O to the electric motor propelling the car T.

The third rail F is in the form of a hollow arch or inverted trough, either rounded or flat internally, as in Fig. 1 or Fig. 7. Its top is usually flat in order to better contact with the sliding shoe M. The electric conductor 75 A (preferably a heavy copper wire or rod) is supported by one or two wooden strips a, suitably channeled to receive it, as in Fig. 1, or by two wooden strips a a', adapted to have the conductor clamped between them by the 80 screw or bolt a', as in Figs. 6 and 7. Referring now to Fig. 1 alone, the said conductor A is shown as resting within the channel of the wooden strip a, which in its turn is supported by the end b' of the rocking arm B. Said arm is formed with a notch b, which fits loosely upon the rounded or bluntly-wedged head of the pivot-spike C and whose end b' is engaged by the finger d' of the post D. The lower end d of said post fits loosely in the hole 90 l of the sleeper or other foundation-strip L, while its upper end is formed with knees or flanges d', by which it is screwed to the under side of the bar E. The guard-rail K protects the said bar from being struck or depressed by any object narrower than the slot 95 between guard-rail and third rail F.

The wheel P, which is shown in Figs. 1 and 4 as carried by the sliding-shoe devices, easily enters the slot containing the bar E and by 100 depressing the latter elevates the electric conductor A into pressing contact with the interior surface of the third rail F. As said wheel rolls along the bar E new points of the con-

ductor A are continually pressed into contact with the third-rail surface above them, while as the said wheel passes such contacting points return to normal positions. It is designed 5 that the weight of the conductor A, the strip a, and the enlarged end b² of the rocking arms B shall more than counterbalance the bar E and the posts D, thereby causing the said conductor to sink to its normal position, as 10 in Fig. 7, when the wheel P has passed. I usually, however, more positively insure such return by providing each post D with a spiral spring S, adapted to raise the posts and bar E, as shown in Figs. 1 and 7.

15 In the modification illustrated in Fig. 7 the main differences over what has already been described consist in separating the bar E by means of an insulated spacing-rail G for a suitable distance from the third rail in order 20 that the posts D may not have to be offset, as in Fig. 1, and also when this third rail is used for street-railways that should a horse's toe-carks enter the slot containing the bar E far enough to raise the conductor A into contact 25 with the rail F the remainder of the shoe and hoof shall not touch the third rail and the horse be thereby electrocuted. To retain said spacing-rail in place, the third rail F is formed with an overhanging shoulder f and 30 the rail G with several lugs g, which reach under the ledge k of the guard-rail K. A suitable insulating material h is introduced between said spacing and third rail of sufficient thickness to thoroughly insulate them 35 when the third rail is alive.

Another modification illustrated in Fig. 7 is the substitution of the two strips a a' for the single one previously described. Said strips are clamped together and to the notched 40 ears b³ of the rocking arms B by means of the screw a², and they so clasp the conductor A as to securely hold it in place. The main purpose for which I design them is to so bind the conductor between them as to keep it 45 from coiling, kinking, or bending, and thereby bring itself into undesired contact with the interior of the third rail. To prevent the bar E and the posts D from being surreptitiously removed from their confining-slot, I form the 50 said posts with the lug d² projecting laterally beneath the ledge k of the guard-rail K.

In the modification illustrated in Fig. 6 the clamping-strips a a', holding the electric conductor A, are bolted to the sliding block B', and the vertical motion of the bar E is made 55 to communicate the desired horizontal reciprocation to said block by means of the pivoted elbow B², the lower end of which engages an eye B⁴ in said block. A strong spiral spring 60 S elevates the bar E and withdraws the conductor A from contact with the side of the third rail F. The spacing-rail G is here employed as in the construction shown in Fig. 7, the only difference being that here the shelf 65 g³ is provided for the support of said spring S. Here also the opening l in the sleeper L passes entirely through the same and serves

for drainage purposes, it being located directly beneath the slot containing the bar E. The other forms of the invention are also furnished with similar drainage-openings, but cannot easily be shown on account of the post D. It will be noticed that the conductor A is here shown as hexagonal in cross-section instead of circular, as in the other figures. The 75 main object of this is to provide a flat surface for contacting with the interior of the third rail, and thereby insure increased surface of electrical contact.

Turning now to Figs. 4 and 5, the construction of the sliding shoe M and its allied parts can be more clearly described. Said shoe is formed with upturned or runner ends, each one-half the width of the shoe. (See n² in Fig. 5.) The carrier N for the shoe is formed 85 with correspondingly-shaped ends n², such ends being laterally perforated for the reception of the fastening-bolts n³, by which the shoe and its carrier are secured together. The carrier N is further formed with the seats, 90 upon which are bolted the lower ends of the S-springs O, whose upper ends are bolted to the part T, which may represent the bottom of the car or a beam secured to the car-truck. The object of said springs is to hold the carrier and shoe in the correct position upon the third rail and at the same time permit the vertical oscillation to which the car-body is liable. Centrally above said carrier N projects a standard N', at whose upper end is an annular enlargement N², within which is revolvably held the thimble P². Revolvable in said sleeve or thimble P², but eccentric with respect thereto, is the shaft P' of the depression-wheel P. The arm r, formed of some 105 non-conducting substance, as wood, is rigidly connected to said thimble P² by means of the hand r' r'', bolted thereto, and is oscillated through the agency of the rod R, controlled in any convenient way by the motorman. 110 When said arm is pulled by said rod, the eccentricity of the thimble and shaft causes the wheel P to descend into the slot containing the bar E; but when the said rod is pushed said wheel is made to rise out from said slot 115 and the third rail made wholly dead. So, also, as the sliding shoe becomes thinner through the effect of its rubbing contact with the rail it is not necessary to pull the rod R quite so far in order to lower the depression-wheel to 120 the point of insuring contact between the conductor and third rail.

As shown in Fig. 1, the hand r' r'' is bolted to the thimble P² through the slot n in the annular head or enlargement N², and said hand 125 not only serves to turn said thimble P², but to retain it in place therein.

In Fig. 10 I show a construction in which the wheel P is held separately from the shoe-carrier N and in which said wheel is prevented from descending too deeply into the slot containing the bar E, and thereby cause a too-heavy pressure upon the latter by means of the auxiliary wheel Q rotating independ-

ently thereof, but preferably mounted on the same axis. This auxiliary wheel rests upon the guard-rail K and so sustains the wheel P at the proper height in the bar-slot. In Fig. 5 1 I show the wheel P itself provided with a flange Q', designed to serve the same purpose.

It will be noticed that the hollow rail F contains the conductor A at so high a point that it will be difficult for water to reach the latter. The air in the upper part of the rail tends to prevent the water from rising therein, and thereby short-circuiting the conductor. To insure greater protection, I insert suitable elastic material between the ends of 15 the rails, as f in Fig. 4, to prevent water and dirt from passing down between and entering the conductor-channel. So, also, I protect the slot through which the rocking arm enters the conductor-channel by surrounding 20 said arm with a rubber collar b⁵, as shown in Fig. 7, or other similar material. Although I have shown but a single rocking arm and post at any one point, it will be understood that said parts are designed to be located 25 at suitable intervals throughout the entire length of the railway. These arms should be from three to four feet apart, depending upon the stiffness of the electric conductor and its supporting-strip and also of the bar E. The 30 said bar should be stiff enough and the distance between the posts D short enough to retain the conductor A in contact with the hollow rail F, even when the wheel P is midway between the posts. On the other hand, 35 such flexibility and distance should be sufficient to enable said conductor to sag out of contact with the rail F at distances of three or four posts in either direction. In this way not more than one or two rails are kept alive 40 at any one moment.

The bar E being composed of separate sections touching end to end, the section immediately beneath the wheel P will be in its depressed condition, while the one following 45 will be in its normal position. Hence the said wheel will meet the end of said latter section with a pronounced shock. To prevent this, I make the bar E practically continuous by means of strap-pieces e, fastened 50 beneath the adjacent ends of the bar-sections by suitable screws e'. Thus arranged the depression of said bar will be a wave motion, wherein the wheel P will be at the hollow.

What I claim as my invention, and desire to 55 secure by Letters Patent, is as follows, to wit:

1. In an electric third rail, the combination of a normally-dead rail formed of conducting material and made hollow throughout its length, a naked conductor extending longitudinally through said rail, fulcrumed arms supporting said conductor out of electric contact with said rail and extending through to the exterior of the latter, and means for automatically actuating said arms and moving 60 said conductor into contact with said rail.

2. In an electric third rail, the combination of the hollow conducting-rail, the movable electric conductor supported therein and normally out of contact therewith, the practically continuous flexible bar located parallel with the said rail, means whereby the depression of a portion of the said bar shall automatically move a corresponding portion of the said electric conductor into electric contact with the said rail, and means carried by a car for locally depressing the said bar and for taking the electric current from the top of the said rail. 70

3. In an electric third rail, the combination of the rail, the movable conductor normally out of contact therewith, the compressible bar adapted to automatically put said conductor and rail in circuit, the sliding shoe adapted to take the current from said rail, and the wheel traveling beside said shoe and adapted 75 to depress said bar. 80

4. In an electric third rail, the combination with the hollow rail and the electric conductor located therein, of the bar having means whereby its depression shall complete the circuit between said conductor and hollow rail, the spacing-rail resting beside said hollow rail and having the lateral lug, and the guard-rail having the ledge overhanging said lug and adapted thereby to hold the spacing-rail in 90 position, said lug being of sufficient length to give ample room for said bar between said guard and spacing-rail, substantially as and 95 for the purpose set forth. 90

5. In an electric third rail, the combination of the hollow rail, the electric conductor located therein but normally out of contact therewith, the rocking arm supporting said conductor, the vertical post having the finger engaging the outer end of said arm, the coiled 100 spring for normally elevating said post, and the bar secured to the upper end of said post, substantially as and for the purpose set forth. 105

6. In an electric third rail, the combination with the hollow rail and the electric conductor located therein, of the rocking arm supporting said conductor, the channeled insulating-strip located between said arm and conductor, and means for depressing the outer end of said arm, substantially as and for the purpose set forth. 110 115

7. In an electric third rail, the combination of the hollow rail, the electric conductor normally out of contact therewith, the separable insulating-strips provided with means for clamping them together and adapted to securely hold said conductor with a portion thereof exposed, and means substantially as set forth for moving said strips and bringing said conductor into contact with said hollow 120 rail. 125

8. In an electric third rail, the combination of the hollow rail, the electric conductor located therein, the rocking arm having the ear, the two wooden strips suitably channeled 130

to partially receive said conductor, the screw adapted to clasp said strips together and fasten them to said ear, and means for depressing the outer end of said arm, substantially as and for the purpose set forth.

9. The combination with a normally-dead third rail adapted to be made temporarily alive by the depression of a bar located at one side thereof, of the sliding shoe pressing upon said rail, the revolute wheel adapted to depress said bar and carried by said shoe, and means whereby said wheel can be raised or lowered at will.

10. In an electric third rail, the combination with the rail, the electric conductor normally out of contact therewith, and the depressible bar located to one side of said rail and parallel therewith and adapted when depressed to put said conductor and rail in circuit, of the sliding shoe, the post rigidly connected therewith and having the annular head, the eccentric thimble loosely held in said head, the wheel having its shaft revolute in said thimble, and means for partially turning said thimble, whereby said wheel can be raised out of contact with or lowered into a depressive engagement with said bar, for the purpose set forth.

11. In an electric third rail, the combination with the same, of the shoe slideable thereon, and having the upturned narrowed ends, the carrier having corresponding ends, the bolts for fastening said ends together, and an elastic connection between said carrier and the ear, substantially as and for the purpose set forth.

12. The combination with the sliding shoe and the carrier holding the same, of the S-shaped springs fastened at their ends to said carrier and to any support connected with the

car, substantially as and for the purpose set forth.

13. The combination of the sliding shoe, the carrier having the post formed with the annular head slotted in its upper periphery, the eccentric thimble loosely held therein, the wheel having its shaft revolute in said thimble, the hand secured to said thimble in said slot, and the insulating-arm held thereby.

14. In an electric third rail, the combination of the electric conductor, the rail normally out of contact therewith, the guard-rail parallel therewith but at a short distance therefrom, the depressive bar located in the slot thus formed and adapted by its depression to complete the circuit between said conductor and rail, the wheel adapted to enter said slot and depress said bar and means connected with said wheel and supported by said guard-rail whereby said wheel is prevented from depressing said bar below a definite limit, substantially as and for the purpose set forth.

15. In an electric third rail, the combination of the rail the guard-rail parallel therewith, the depressible bar beside said guard-rail adapted by its depression to put an electric conductor into contact with said third rail, the wheel adapted to roll upon said bar and depress it, and the auxiliary wheel rolling upon said guard-rail and adapted to prevent said bar from being depressed too far, substantially as and for the purpose set forth.

In testimony that I claim the foregoing invention I have hereunto set my hand this 22d day of March, 1898.

LOWELL MASON MAXHAM.
